WARM AIR FURNACE

Allen P. Livar, Dayton, Ohio, assignor, by mesne assignments, to Chrysler Corporation, Highland Park, Mich., a corporation of Delaware

Application June 17, 1938, Serial No. 214,186

3 Claims. (Cl. 126—99)

This invention concerns improvements in the construction, arrangement and details of a warm air furnace which may be fired by any suitable means such as oil or gas burners.

The primary purpose of this construction is to provide the most efficient heat transfer between the flue gases and the air to be warmed, whereby a small, light, inexpensive furnace, from one-third to one-half cheaper and smaller than existing furnaces of the same capacity, may be provided for house heating. Another purpose of the present invention is to provide a furnace which is easily assembled and which will occupy as little space as possible in order that the furnaces may be installed in utility closets on the floor to be provided with warm air; whereas previous furnaces have been of such size that the furnace is usually installed in the basement of the house. The third purpose of the present invention is to design a furnace which is quiet in operation in order that the furnace may be installed adjacent the space to be conditioned. A fourth purpose of the present invention is to provide a furnace having all of the foregoing advantages in which all radiant, heat-transferring surfaces are wiped by moving streams of air to be warmed. A fifth purpose of the present invention is to provide a furnace wherein the radiant surfaces are surrounded by moving streams of air and are suitably spaced from the jacket of the furnace in order that the furnace jacket may not become overheated, some of the spacing and insulation being provided by heat exchanging surfaces which are in turn contacted by moving streams of air to be warmed. A sixth purpose of the present invention is to provide a construction wherein the flue gases are caused to travel through small heat exchangers arranged in parallel, whereby the greatest transfer of heat from the flue gases to the air to be warmed is achieved.

Other purposes and advantages of the present invention will be apparent from a study of the following specification taken in connection with the accompanying drawings wherein like numerals refer to like parts throughout. In the drawings, Fig. 1 is a front elevation of one size of furnace embodying my present invention; Fig. 2 is a side elevation of the furnace shown in Fig. 1; Fig. 3 is a cross section taken along line 3—3 of Fig. 2 looking in the direction of the arrows; Fig. 4 is a cross section taken along line 4—4 of Fig. 2 looking in the direction of the arrows; Fig. 5 is a vertical section taken along line 5—5 of Fig. 3, showing the means of an-

choring a baffle in the heat exchangers; Fig. 6 is a side view on a small scale of a portion of the present furnace having an oil-burning device attached thereto; and Fig. 7 is a view similar to view 6 showing a portion of a furnace having a gas burner attached thereto and illustrating the interchangeability of firing means for the present type of furnace.

The furnace construction comprises a jacket 10 which surrounds the firebox, heat exchangers, blowers and filter comprising the operating parts of the furnace, and which is provided with an inlet 11 which may be connected to a duct or left open to the room. The inlet 11 is preferably adjacent the bottom of the furnace, and the outlet 12 is preferably adjacent the top of the furnace in order to take advantage of natural draft in addition to forced draft provided by blowers 13 located in the bottom portion of the furnace and driven by a suitable motor 14. The blowers draw air inward through the opening 11, and through a filter 15 interposed between the opening and the inlet to the blowers. The blowers and motor are suspended from a blower deck 16 suitably supported by legs 17 and cross braces 18. The walls of the jacket 10 and the blower deck 16, together with the lower surfaces of the firebox and heat exchangers, form a plenum chamber 20 into which the air is discharged by the blowers 13. An access door 21 is preferably provided in order to service the motor 14 and blowers 13, the same being provided with removable fastening means 22.

The upper ends of legs 17 are joined by angles 25 upon which are supported the firebox and heat exchanger construction. The firebox preferably comprises a rectangular enclosure 26 of considerable height with respect to its cross-sectional dimensions, having parallel upwardly extending walls except for one wall (preferably the rear wall) which extends upwardly to a point adjacent the hottest flame region and then diagonally inward and upward toward the opposite wall to form an inclined crown sheet 27 above the hottest portion of the flame rising upwardly 45 from the burner 28. The upper front corners of the firebox are provided with laterally extending flues 29 which extend into the upper front corners of parallel heat exchangers 30 and 31. The heat exchangers are substantially rectangular in shape and of the same height as the firebox, narrow in width, and extending from front to rear of the furnace from a point adjacent the front wall of the firebox to a point rearwardly of the rear wall of the firebox. The upper rear

corners of the heat exchangers are joined by a lateral exhaust flue 32 which is preferably triangular in cross section as formed by extending the top and rear walls of the heat exchangers, 5 and an inclined flue sheet 33 extending inwardly and upwardly, and parallel to the crown sheet 27. The heat exchangers are spaced from the jacket walls in order to provide passages for moving streams of air entirely around all of the heating surfaces, and the heat exchangers and rear wall of the firebox provide a passage 34 of substantial dimensions extending upwardly into the inclined, forwardly extending passage 35 defined by the crown sheet 27 and flue sheet 33 whereby 10 to provide means for moving a substantial quantity of air over the hottest portion of the firebox. The heat exchangers are laterally spaced from the side walls of the firebox to provide passageways for substantial quantities of air adjacent the radiant side walls of the firebox, and there is likewise a substantially large passage 15 adjacent the front walls of the firebox and heat exchangers. All of these passages lead upwardly into a free space above the top of the firebox 20 and heat exchangers, and the air moves through the passages and free space into the outlet opening 12 which occupies a considerable portion of the front portion of the jacket top. The inclined passageway 35, which conducts the hottest 25 air, extends forwardly and terminates adjacent the opening 12 so that the hottest air is conducted into the outlet opening. Likewise, the uppermost portion of the firebox 26 and the lateral flues 29 are substantially centrally positioned with respect to the opening 12 so that radiant heat therefrom will not overheat any portion of the jacket.

The heat exchangers are provided with baffles 40 which are fastened to the top wall thereof 40 and extend downwardly toward the lower wall thereof along a line substantially dividing the heat exchangers into two vertical sections, the forward section conducting the hot flue gases downwardly from the lateral flues 29, and the 45 rearward section conducting the cooler flue gases upwardly into the exhaust flue 32 where the parallel streams of flue gases are combined and exhausted through a smoke stack 41. It is to be noted that the blowers 13 are preferably 50 mounted so as to throw the greatest volume of air forwardly into the plenum space 20 whereby a greater quantity of moving air will tend to wipe across the front of the firebox and the forward portions of the heat exchangers than at the rear of the firebox and heat exchangers.

The firebox is preferably provided with a relief opening and vent passage 45 which is closed by a gravity-actuated explosion door 46 as is usual in furnace construction. The heat 55 exchangers are also preferably provided with forwardly extending cleanout passages 47 which extend through the jacket and are closed by removable plates 48 in order that any soot collected in the heat exchangers may be removed from time to time.

The baffles 40 are preferably rigidly fastened to the top surface of the heat exchangers and hang downward therein, and the lower ends

thereof are hooked at 51 about bolts 50 passing through the walls of the heat exchangers. Expansion of the baffles 40 is permitted by the loose connection, the baffles being guided by the bolts 50 and the hooked lower ends 51. The bolts act as tie-rods to prevent the walls of the heat exchangers from reverberating and the baffles act as spacers for the tie-rods.

The burner 28 is suitably mounted in the firebox by rigidly fastening the same to a removable cast-iron burner plate 60 which is fastened to the front wall of the firebox by bolts 61 and sealed thereto by an asbestos gasket 62. As seen in Figs. 6 and 7, the burner plate 60 may be replaced by a suitable burner plate 60' which is so fashioned as to provide a means of supporting an oil burner 28' instead of the gas burner 28.

The furnace may be controlled by any suitable automatic or manual control system, as is well known in the art, the control system being no 20 part of my present invention. The present invention is fully illustrated in the accompanying drawings and described in the foregoing specification, and it should be readily apparent to those skilled in the art that the same permits of modification in arrangement and detail, all of which are considered a part of my invention as 25 determined by the scope of the following claims.

I claim:

1. A warm air furnace comprising a substantially rectangular firebox having an inclined crown sheet, a substantially rectangular heat exchanger of substantially the same height as said firebox at each side of said firebox and spaced therefrom, a lateral flue extending from each of a pair of adjacent upper corners of said firebox near the top thereof and providing passageways for flue gases to pass from said adjacent upper corners of said firebox into the upper adjacent corners of said heat exchangers, a 40 baffle in each heat exchanger extending downward from the top wall thereof and ending above the bottom wall thereof whereby to divide each heat exchanger into a downwardly extending portion and an upwardly extending portion to 45 cause the flue gases to flow downward then upward through said heat exchangers, a lateral, substantially triangular exhaust flue joining the other upper corners of said heat exchangers, and an exhaust stack extending from said exhaust 50 flue, said exhaust flue having a side substantially parallel to and spaced from said inclined crown sheet whereby to form an air duct passing directly over the flame area of said firebox.

2. The structure set forth in claim 1, in which 55 said side of said exhaust flue projects beyond the adjacent side of said firebox in order to divert an upwardly moving stream of air into said air duct.

3. The structure set forth in claim 1, in combination with a jacket enclosing said firebox and flues and spaced therefrom in order to define air 60 passages surrounding the heat exchanging surfaces, said jacket being provided with an outlet opening for the warm air located above the top 65 of said firebox and adjacent the outlet to said air duct.

ALLEN P. LIVAR.
